UNITED STATES PATENT OFFICE.

JOSEPH F. JOHNSON, OF LONG BEACH, MISSISSIPPI, ASSIGNOR OF ONE-HALF TO
DOMINICK W. STEPISIEH, OF LONG BEACH, MISSISSIPPI.

SANITARY MEASURE AND FUNNEL COMBINED.

1,327,389.

Specification of Letters Patent.

Patented Jan. 6, 1920.

Application filed March 8, 1918. Serial No. 221,233.

To all whom it may concern:

Be it known that I, JOSEPH F. JOHNSON, a citizen of the United States, residing at Long Beach, in the county of Harrison and 5 State of Mississippi, have invented certain new and useful Improvements in Sanitary Measures and Funnels Combined; and I do hereby declare the following to be a full, clear, and exact description of the invention, such as will enable others skilled in 10 the art to which it appertains to make and use the same.

My invention relates to improvements in that type of funnel and measure combined 15 wherein regulated quantities may be dispensed from the measure at the will of the operator.

The object of this invention is to provide a measure equipped with a novel sliding 20 valve which closes the communication between the funnel spout and measure body and is operated so as to permit a regulated amount of the contents of the measure to be dispensed at the will of the operator.

25 A further object of this invention is to provide a combined measure and funnel of this character, which will be simple, practical and comparatively inexpensive in construction and one that can be manufactured 30 and sold at a low cost.

With these and other objects in view, the invention consists in the novel combination and arrangement of parts hereinafter more fully described and set forth in the claims 35 hereto appended.

In the drawing:

Figure 1 is a vertical longitudinal sectional view of a measure and funnel as made in accordance with this invention.

40 Fig. 2 is a transverse sectional view taken on the line 2—2 of Fig. 1.

Fig. 3 is a detail sectional view taken through the body.

Like numerals of reference designate corresponding parts in all the figures of the drawing.

Referring to the drawing, the numeral 5 designates the body of the measuring receptacle and it has one end fully open. The 50 body has secured to its bottom a plurality of spaced legs 6 to hold the body in upright position when being filled or not in use. The bottom is also provided centrally with an outlet opening 7 and secured to the wall

of this opening and depending therefrom is 55 a substantially funnel shaped spout 8. The body 5 is provided with a vertical slot 9 and has secured to the interior thereof at a point adjacent each vertical wall of the slot an angle bracket 10 and these angle brackets 60 are adapted to form a slot in which is secured a graduated glass 11 so that the contents of the receptacle may be readily and easily determined.

A cover 12 is hingedly secured to the upper edge of the body as at 13 and this cover has a tight connection with the body when closed so as to form an air tight closure.

A handle 14 is secured vertically to the 70 wall of the body exteriorly thereof and this handle provides means whereby the body or receptacle may be easily transported from one place to the other as desired.

A casing 15 is secured to the bottom of the receptacle or body 5 and has one end secured to and communicating with the spout 8 at its point of juncture with the bottom of the receptacle. The opposite end of the casing terminates flush with the peripheral edge of the bottom and has secured therein a screw threaded cap 16 which is provided with a central opening through which an operating rod 17 slides. A valve 18 is secured to the inner end of this rod and is adapted to be normally located in the spout 8 to close the opening 7, thus closing the communication between the spout 8 and receptacle or body 5. A coiled spring 19 is located within the casing 15 and surrounds the rod 17 and has one end secured to the 85 cap 16, thus it can be seen that when the rod is drawn rearwardly or out of the casing 15 that the valve 18 will be urged against the tension of the spring into the casing 15 and open communication between the body 5 and spout to permit its contents to be readily dispensed therefrom and upon the inward movement of this rod the valve will seek its initial position thus closing the communication between the body 5 and spout 8.

90 A spring operating member 20 has one end secured as at 21 to the wall of the body 5 and its opposite end secured to the outer end of the rod 17. The portion of the operating member 20 located within the handle 14 and parallel therewith is adapted to 95 be grasped by the hand of the operator positioned about the handle 14 so that he may 100

105

withdraw the valve 18 from its seat in the spout and dispense a predetermined amount of the contents of the body 5 as desired.

A flat valve opening outwardly is hing-
edly secured as at 23 to the terminal of the
spout 8 and this valve is adapted to be nor-
mally closed and actuated by the contents
of the body 5 passing into the spout 8, thus
it can be seen that the spout will always be
kept in a clean and sanitary manner when
not in use.

The handle 14 is substantially U-shaped
and is provided in its bottom with a slot
receiving the lower end portion of the mem-
ber 20. The U-shaped handle 14 forms a
gripping element for drawing the spring 20
outwardly.

A spring catch 24 is secured to the handle
14 at the lower portion thereof and is off-
set outwardly intermediate its ends as at 25,
and this offset portion is adapted to con-
stitute a stop and is adapted to engage the
operating member 20 when forced rear-
wardly to hold the valve 18 unseated and
establish a communication between the spout
8 and body 5.

In use, the valve 18 is seated as illus-
trated in Fig. 1, the cover 12 is raised and
the body 5 filled with a suitable liquid to
be dispensed. The contents in this body 5
may be readily determined by the graduated
glass 11. When it is desired to dispense a
predetermined amount of the contents of
the body 5 it is only necessary to grasp the
handle 14 and 20 and by pulling rearwardly
on the member 20 unseat the valve 18 and
permit a certain amount of the contents of
the body 5 to run down into the spout 8

and out into a suitable receptacle. When
the desired amount has passed into the spout 40
8 it is only necessary to release the member
20 from the stop 25 and by the action of
the spring 19 the valve 18 will be seated thus
closing the communication between the
spout 8 and the body 5.

Having thus described my invention what
I claim is:

1. A device of the character described in-
cluding a container having a discharge opening
in its bottom, a valve for said opening, 50
a casing secured to the bottom of the con-
tainer and slidably receiving said valve, a
valve rod connected to said valve and ex-
tending through said casing, a U-shaped
member secured to one side of the container 55
and having a slot in its bottom, an upright
flat operating spring disposed within said
U-shaped member, said operating spring
being secured at its upper end to said con-
tainer and having its lower end portion 60
extended through the slot in the U-shaped
member and connected to said valve rod,
and a catch carried by said U-shaped mem-
ber for locking said operating spring, said
operating spring being adapted to be drawn 65
toward said U-shaped member for operating
the valve.

2. The construction set forth in claim 1,
and spring means carried by said valve rod
for normally retaining the valve closed. 70

In testimony whereof I affix my signa-
ture in presence of two witnesses.

JOSEPH F. JOHNSON.
